US0D1070209S

(12) **United States Design Patent** (10) **Patent No.:** **US D1,070,209 S**
(45) **Date of Patent:** **** Apr. 8, 2025**

(54) **VACUUM**

(71) Applicant: **Ningbo Shijia Cleaning Tools Co., Ltd.**, Zhejiang (CN)

(72) Inventor: **Hui Hu**, Zhejiang (CN)

(73) Assignee: **Ningbo Shijia Cleaning Tools Co., Ltd.**, Ningbo (CN)

(**) Term: **15 Years**

(21) Appl. No.: **29/847,903**

(22) Filed: **Jul. 28, 2022**

(30) **Foreign Application Priority Data**

May 9, 2022 (CN) 202230268061.1

(57) **CLAIM**

The ornamental design for a vacuum as shown and described.

DESCRIPTION

FIG. 1 is a front view of the vacuum showing my new design;

FIG. 2 is a back view thereof;

FIG. 3 is a right side view thereof;

FIG. 4 is a left side view thereof;

FIG. 5 is an enlarged top view thereof;

FIG. 6 is an enlarged bottom view thereof;

FIG. 7 is a perspective view thereof in an upright position; and,

FIG. 8 is another perspective view thereof in a tilted position.

The broken lines in the figures show portions of the vacuum, which form no part of the claimed design.

1 Claim, 8 Drawing Sheets
